COMBINATION MOTOR AND BLOWER UNIT

George J. Shomphe, Nashua, N. H., assignor to Sanders
Associates Incorporated, Nashua, N. H.

Application October 15, 1953, Serial No. 27,187

Term of patent 14 years

(Cl. D26—5)

Fig. 1.

Fig. 2.

Fig. 3.

Fig. 4.

Fig. 5.

To all whom it may concern:

Be it known that I, George J. Shomphe, a citizen of the United States of America, residing at 59 Wood Street, city of Nashua, county of Hillsborough, and State of New Hampshire, have invented a new, original, and ornamental Design for a Combination Motor and Blower Unit, of which the following is a specification, reference being had to the accompanying drawing, forming a part thereof.

Figure 1 is a front perspective view of a combination motor and blower unit, showing my new design;

Figure 2 is a rear elevational view thereof;

Figure 3 is a front elevation thereof;

Figure 4 is a side elevation thereof taken from the side opposite the front side of Figure 1; and Figure 5 is a bottom plan view thereof.

I claim:

The ornamental design for a combination motor and blower unit, substantially as shown.
